UNITED STATES PATENT OFFICE

GEORGE M. ETNYRE, OF OREGON, ILLINOIS, ASSIGNOR TO E. D. ETNYRE & COMPANY, INC., OF OREGON, ILLINOIS, A CORPORATION OF ILLINOIS

DISTRIBUTOR FOR ASPHALT AND LIKE LIQUIDS

Application filed June 1, 1929. Serial No. 367,785.

The invention pertains generally to apparatus for applying liquid bituminous materials such as asphalt and similar products to roadways, and more particularly has reference to the distributing system thereof.

The general object of the invention is to provide a machine of this character embodying a novel distribution system of high efficiency and simple and practical construction.

An important object of the invention resides in the provision of a new and improved system for distributing asphalt, which system includes means for thoroughly draining, removing, or expelling asphalt material from the system, and principally from the discharge end thereof, at the time the system becomes inoperative, whereby clogging of the system by the asphalt is prevented.

Still another object of the invention is to provide an asphalt distributing system in which a blast of heated air may be forced through the system to expel or remove the asphalt therefrom.

Other objects and advantages will become apparent in the following description and from the accompanying drawings, in which:

Figure 1 is a rear end view of the distributor truck showing the tank, the distributing pipes and controls.

Fig. 2 is a detail view showing the pump and intake.

Fig. 3 is a side view of the rear end as shown in Fig. 1.

Fig. 4 is a perspective view of the distributing system and controls, the housing therefor being shown in broken outline.

Fig. 5 is a diagrammatic illustration of the circulation and discharge system of the machine.

In general the machine organization to which the invention relates comprises a supply reservoir or tank having a system of pipe connections leading therefrom for distributing asphalt from the tank onto a road surface. A force pump is interposed in the pipe connection leading from the tank, and a three-way valve controls the flow of fluid in the operation of the pump, either through the intake pipe into the pump and to the

tank, or from the tank through the pump and to the distributing system. The distributing system is enclosed by a housing and means are provided for applying heat to the interior of the housing whereby any asphalt remaining in the system may be liquefied preparatory to starting the operation of the system. Means is also provided for forcing hot gas or air from the interior of the housing through the distribution system immediately after the system has ceased operation, so that any asphalt remaining undischarged from the system will be expelled therefrom by the current of hot air.

In practice the distributor comprises a support which may be a frame 10 adapted to be mounted on a motor truck. 11 indicates the main reservoir or tank into and from which the fluid to be discharged is filled and discharged by operation of a pump 12. The pump 12 is arranged to be operated from a suitable source of motive power, such, for example, as an internal combustion engine 13. The pump, of course, may be operated from the motor truck but the independent engine 13 is preferably employed so that the speed of the pump may be controlled independently of the speed of the vehicle.

The tank 11, which may be of any suitable construction, is provided with heating means 80 of any preferred type, that herein shown including internal heating flues 14, certain of which communicate between an end chamber 15 provided at one end of the tank and a similar chamber (not shown) at the other 85 end of the tank. Heaters (not shown) within a housing 16 supply hot gases to said flues. The pump 12 (Figs. 1, 2 and 3) is preferably of the positive type and is located almost directly beneath the rear end of the tank 11, 90 being separated therefrom only by the casing of a valve 17. Said valve is of the three-way type and its casing communicates at its upper end with the bottom of the tank through an aperture 18 (Figs. 1 and 2) and at its lower end with the inlet opening of the pump 12. An intake pipe 19, extending laterally of the frame 10, communicates with one side of the valve casing. When the tank is to be filled the outer end of the pipe 19 is connected to a 100

source of supply. The valve member 17^a (Fig. 2) is preferably in the form of a three-way valve arranged, in one position thereof, to control the flow of fluid from the tank to the 5 pump and thence to the distributing system. The valve, in another position thereof, directs the flow of liquid through the intake pipe to the pump by which it is forced to the tank through connections to be presently described. 10 A hand rod 20, operatively connected to the valve member 17^a, extends to a position on the machine convenient to the operator. 15 The pump 12 is drivingly connected with the engine 13 under the control of a clutch 20 within the housing 21. The motor or clutch is geared to the pump shaft by means of the gears in the gear case 22. The discharge end of the pump 12 communicates, through the medium of a downwardly and rearwardly 25 extending flange connection 23, with headers 24 and 25 which are rigidly secured to said connection and extend transversely of the frame in opposite directions from the connection. At the outer end of each of said 30 headers there is secured a rearwardly and horizontally disposed pipe 26, preferably secured to the headers by welding. In each of said pipes a valve 27, 27^a is interposed, which is of the three-way type so as to control 35 the flow of liquid through the pipes 26 and also to control the discharge of the fluid into circulatory pipes 28, 28^a extending inwardly from said valves. The flow of fluid through each of the pipes 28, 28^a is in turn 40 controlled by interposed shut-off valves 29, 29^a. The inner ends of the pipes 28, 28^a communicate respectively with the lower ends of a U-shaped circulating pipe 30 which extends upwardly into the interior of the tank 45 11 and is provided at the top thereof with a discharge pipe 31. Each of the valves 27, 27^a communicates through pipes 31^a with distributors or spray bars 32, 32^a arranged to distribute an even film or layer of the asphalt 50 upon the road bed.

Referring particularly to Fig. 4, the manual means for controlling the flow through the distributing system will now be described. The valves 27, 27^a are provided with upwardly extending operating spindles 33, 33^a, respectively, and similar but shorter operating shafts 34, 34^a extend upwardly from the valves 29, 29^a. The operating mechanism is arranged so that any one valve of one set, and 55 the non-similar valve of the other set, may be simultaneously operated, and further is arranged so that all operations are performed from substantially the same point for the convenience of the operator. Thus, mounted on 60 the upper end of one of the spindles (illustrated in Fig. 4 as being the left hand spindle 33) are two similar hand levers 35 and 36. The upper lever 35 is rigid with the spindle 33, while the lower lever 36 is free to turn there- 65 on. The other spindle 33^a carries a short rigid

crank arm 37 at its upper end which is linked by a bar 38 to the loose hand lever 36. This construction permits the levers 35 and 36 to operate the valves 27, 27^a, respectively, independently of each other. 70

Each of the spindles 33, 33^a and the shafts 34, 34^a have rigid therewith crank arms 39, 40, 41 and 42, (Fig. 4) of which the arms 39 and 42 are in substantially the same horizontal plane, while the arms 41 and 40 are in another horizontal plane. Rigid links 43 and 44 connect the respective pairs of crank arms 39, 42, and 41, 40. Thus actuation of the hand levers 35 and 36 operates the valves 29, 29^a as well as the valves 27, 27^a. 75

The operation of the fluid flow system is as follows: When the tank 11 is to be filled, the flow of liquid, through the spray bars 32, 32^a, is prevented by closing the valves 27, 27^a by means of the hand levers 35, 36. In 80 the closed position of the valves 27, 27^a the respective circulatory valves 29, 29^a will be open so that there is communication from the pump to the tank by way of the inverted U-tube 30 and the depending pipe 31. The valve 17, between the tank 11 and the pump 12, is, during this operation, in such position that the pump operates to draw liquid 85 through the intake pipe 19, in which position of the valve the aperture 18, between the 90 valve and the tank, is closed. The incoming liquid is forced by the pump through the flange connection 23, the headers 24 and 25, the two sets of valves 27—29 and 27^a—29^a, the U-tube 30, and pipe 31 into the tank 11. When the tank is full, the valve 17 is turned 95 to cut off the intake pipe 19 and to establish communication of the pump with the tank 11 through the aperture 18. If the operation of the pump, at this time, is continued the liquid 100 will be drawn from the bottom of the tank and returned thereto through the circulatory system described in the operation of filling 105 the tank.

When the liquid is to be distributed upon 110 the road by both spray bars 32, 32^a, the hand levers 35 and 36 are moved to the opposite position, opening the valves 27, 27^a to permit fluid to flow through the spray bars and cutting off communication with the circulatory system. If only one of the spray bars 115 32 or 32^a is to be used, the operating handle controlling the valve 27 or 27^a for the desired distributor is moved to open the valve, thus establishing communication with that spray 120 bar and interrupting the flow of fluid through that side of the circulatory system. Simultaneously, the opposite valve 29 or 29^a, which controls the flow of fluid through the opposite side of the circulatory system, is moved 125 to its closed position through the associated crank arms and connecting link 39, 42, 43 in one instance, and 41, 40, 44 in the other (see Fig. 4).

In use there will frequently occur consider- 130

able periods of time in which the distributing apparatus is idle as, for example, when the vehicle is moving from a loading point to a distributing point, or back to the loading point after the load has been distributed. At such times the bituminous material may have a tendency to solidify or "freeze" in the pipes of the distributing and circulatory systems and in the interposed valves. 1, therefore, provide a heating means for distributing heat to substantially all of the exposed parts of the distributing and circulatory systems. To this end a housing 45 encloses the lower portion of the distributing and circulatory systems including the valves 27, 27^a, 29, 29^a and the associated pipe connections, which housing has a rearwardly and upwardly extending communicating portion 46. The portion 46 encloses the flange connection 23, pump 12 and valve 17. Within the lower portion of the housing 45 is a radiator 47 (Fig. 4) arranged with one end opening outwardly through a suitable aperture in the rear wall of the housing and having the other end constructed to form a discharge mouth 47^a for directing a flow of heated air through the housing portion 46. Opposite sides of the radiator are provided with communicating tubes 48 for discharging a current of heated air at points substantially adjacent the control valves.

A burner 49, mounted at the open mouth of the radiator 47, heats the radiator and heated air is discharged into the interior of the housing from the tubes 48 and discharge mouth 47^a. The burner 49 is preferably mounted permanently at the mouth of the radiator 47 and normally burns continuously while the machine is in use. However, if desired a removable burner may be employed in which event the housing might be heated intermittently. By this construction heat is efficiently applied to substantially every part of the distributing and circulating systems, thereby insuring that the machine may be quickly conditioned for use and cannot become clogged during use.

It will be observed, however, that the connecting pipes 31^a which convey the liquid from the valves 27, 27^a to the spray bars 32, 32^a and the spray bars themselves, cannot be confined in the housing 45, and it has been found, particularly where heavy bituminous material is being distributed, that there is a tendency for the spray bars and the discharge nozzles therein to become clogged. Means is provided, therefore, for insuring a complete discharge of all of the asphaltic material from the spray bars, and the connecting pipes leading thereto, after a distributing operation has been completed. In this embodiment, such means comprises a connection between a source of hot air, namely, the housing 45 and the pump 12 whereby the pump may be used to force hot air through

the distributing pipes and the spray bars.

Referring to Figs. 1 and 4, one end of the housing 45 is apertured to receive a pipe connection 50 which preferably includes a section of flexible tubing 51. The free end of the pipe connection 50 is arranged to be connected to the outer end of the intake pipe 19. Preferably the means for establishing the connection between the pipes 50 and 19 is of such character that the connection may be rapidly and easily established. A suitable means for this purpose, as shown in Fig. 2, comprises a yoke member 52 straddling the free end of the pipe connection 50 and pivotally secured thereon. The yoke 52 is also capable of longitudinal sliding movement relative to the pivotal points, and the free ends of the lugs of the yoke are formed to provide hooks 53 adapted to engage diametrically opposed lugs 54 on the outer end of the intake pipe 19. A screw 55, carried by the intermediate portion of the yoke 52, engages an underlying portion of the connection 50 to draw the two ends of the pipes 50 and 19 into tight abutment. It is usually desirable to have the means for clearing out the distributing system ready for instant use, hence the pipe connection 50 is generally connected to the intake pipe 19, as shown in Figs. 1 and 5, immediately after filling the tank 11.

In describing the operation for clearing the asphalt from the distributing system, it will be considered that the machine is just completing a distributing operation and that the operator wishes to expel the asphalt from the distributing system. At this time the valve 17 (see Fig. 5) and the valves 27, 27^a are open to permit a flow of fluid from the tank to the spray bars 32, 32^a. The valves 29, 29^a are closed so that the full force of the pump is utilized in forcing the asphalt from the spray bars. The pipes 50 and 19 communicate with each other, and the burner 49 is operating to heat the interior of the housing 45.

At the instant the operator wishes to discontinue further distribution, the valve handle 20 is operated to move the valve 17 to establish communication between the intake pipe 19 and the pump 12. This movement of the valve closes the aperture 18 preventing further flow of asphalt from the tank 11. The pump now operates to draw heated air through the intake pipe 19 from within the housing 45 and to force said air through the flanged connection 23, headers 24, 24^a, pipes 26, valves 27, 27^a, pipes 31^a to discharge from the spray bars 32, 32^a. It will be apparent that heated air is thus forced into the distributing system immediately after the flow of asphalt from the tank has ceased so that all of the asphalt remaining in the distribution system, including the main valve 17 and the pump 12, will be completely expelled. Thus, solidifying of the bituminous material

in the system and spray bars is prevented and the disadvantages resulting therefrom eliminated.

While it is contemplated that unheated air might be used in clearing the distributing system of the lighter asphalts, it has been found that heated air is much more advantageous inasmuch as the heated air tends to maintain the asphalt in its liquid condition during the clearing operation, while cold air will in itself solidify some of the asphalt. The operation of the asphalt expelling means has been described with the machine controls in position to distribute from both spray bars, but it will be understood that the heated air may be directed through either one of the spray bars singly by merely setting the controls in the proper manner.

From the foregoing it will be evident that the clearing operation may be easily and quickly accomplished by a single operative movement and that the machine parts may also be as readily returned to their original positions either for continued distribution or for refilling the tank. In the first event, it is not necessary to remove the pipe connection 50 from the intake pipe 19, but if the tank is to be filled, then said connection is removed and a pipe line from a source of supply is connected to the intake pipe.

I claim as my invention:

1. A liquid distributing system comprising, in combination, a liquid supply tank, a discharge line therefrom, a pump interposed in said line, a valve in said line on the inlet side of said pump, an intake pipe communicating with said valve, said valve being arranged in one position to control a flow through said discharge line and in a second position to direct a flow through said intake pipe into said discharge line, a source of heated gas, and means connecting said source with said intake pipe to permit a current of heated air to be forced through said discharge line by said pump.

2. A liquid distributing system comprising, in combination, a liquid supply tank, a discharge line therefrom, a pump interposed in said line, a valve in said line on the inlet side of said pump, an intake pipe communicating with said valve, said valve being arranged in one position to control a flow through said discharge line and in a second position to direct a flow through said intake pipe into said discharge line, a housing enclosing parts of said discharge line, means for heating the interior of said housing and means connecting said housing with said intake pipe whereby when said valve is positioned to connect said intake pipe with said discharge line a current of heated air is drawn from said housing and passed through said discharge line.

3. A fluid distributing system comprising, in combination, a tank, a discharge line con-

nected to said tank, a pump arranged to force fluid through said discharge line, an intake pipe, a control valve connected to said intake pipe and interposed in said discharge line between said tank and pump for controlling the flow of fluid from said tank to said discharge line in one position and for directing a flow of fluid from said intake pipe to said discharge line in another position thereof, a source of heated gas, and means connecting said source with said intake pipe whereby movement of said control valve from said tank and discharge line connecting position to said intake pipe and discharge line connecting position immediately permits hot air to be passed through said discharge line to expel the fluid from said discharge line.

4. A fluid distributing system comprising, in combination, a tank, a discharge line, means connecting said discharge line with said tank including a control valve connected to said tank and a force pump connected to said valve and discharge line, an intake pipe also controlled by said valve, a housing substantially enclosing said discharge line and pump, means for heating the air within said housing, a conduit having one end communicating with the interior of said housing, and means on the other end of said conduit for detachably connecting said end with said intake pipe to permit heated air to be withdrawn from said housing into said intake pipe.

5. A fluid distributing system comprising, in combination, a tank, a discharge line, means connecting said discharge line with said tank including an interposed control valve and force pump, an intake pipe also controlled by said valve, a source of heated gas, a conduit connected to said source of gas, and means detachably connecting said conduit with said intake pipe.

6. A fluid distributing system comprising, in combination, a source of fluid, a discharge line connected thereto, a source of heated gas, a conduit connected thereto, a distributing system of conduits, a single control valve connecting said discharge line and said heated gas conduit with said distributing system and arranged to direct a flow from one or the other to said system, and a pump interposed between said valve and said distributing system.

7. In a fluid distributor, the combination of a fluid tank, a discharge system connected to said tank for distributing fluid therefrom, and means for supplying said system with heated gas comprising a heating casing substantially enclosing said discharge system, means for heating the interior of said casing, and a conduit interposed between said casing and said system.

8. In a fluid distributor, the combination of a fluid tank, a discharge line, a conduit connecting said line with said tank, a second

conduit connecting said line with a source of heated gas, a control member interposed between said conduits and said line for selectively controlling the flow from either of said 5 conduits to said line so that heated gas may be passed through said line immediately after the flow of fluid therethrough has been shut-off, a casing substantially enclosing the parts connected to said control member on the discharge line side thereof, and means 10 for heating the interior of said casing thereby heating said enclosed parts and at the same time providing a source of heated gas.

In testimony whereof, I have hereunto 15 affixed my signature.

GEORGE M. ETNYRE.
